UNITED STATES PATENT OFFICE.

HARRY T. WRIGHT, OF ROCKLAND, AND WALTER A. BROWN, OF BROCKTON, MASSACHUSETTS.

LAST.

1,370,574.

Specification of Letters Patent.

Patented Mar. 8, 1921.

Application filed January 26, 1920. Serial No. 354,190.

To all whom it may concern:

Be it known that we, HARRY T. WRIGHT and WALTER A. BROWN, citizens of the United States, residing at Rockland and 5 and Brockton, respectively, in the county of Plymouth and State of Massachusetts, have invented certain new and useful Improvements in Lasts, of which the following is a specification.

10 This invention relates to lasts. More particularly it relates to means for preventing the creeping, wrinkling or yielding of the edge of an inner sole while it is tacked or otherwise fastened on the last during the 15 process of shoe making.

In the art of making shoes as at present practised it is a common experience that the pulling over operation or the bed machine operation causes the edge of inner sole to 20 be pushed back a little from the edge of the last, wrinkling it or pushing it sidewise, the latter being particularly likely to happen during the welting operation, so that the finished shoe fails of perfect form and is 25 more or less bulgy and uneven either at the tip or on one side of the toe or in the seam. It is an object of the present invention to make the toe perfect in these respects, by preventing wrinkling or slipping of the 30 edge portions of the inner sole, and to make the operation of the later machines uniform and accurately proper as regards margin of trimming and stitching, with the result of enabling the workman of ordinary skill, 35 and with only ordinary care and without additional cost for labor or on the operation, to produce a regular quality of shoe equal to that which hitherto has been possible only by the craft of an unusually 40 skilled workman carried out with extraordinary care. Super-added to this, an advantage of the invention found in practice is that the superior results stated can be obtained with a thinner inner sole, enough to 45 make a material reduction in cost of shoes. These results are attained by providing the device which is herein termed a stabilizer. This can be made in various ways, one of which is shown for illustration as an ar- 50 rangement of spurs close to the edge of the last at the toe, surrounding the tack or other fastening by which the inner sole is there held to the last, so arranged that they become embedded in the inner sole and pre- 55 vent the latter from slipping back from the

edge of the last when a push is exerted upon the inner sole, from those edges, by the various operations of lasting, and pointing forward so that the last can be removed from the inner sole by pulling to the rear. The 60 points being so close to the edge that the leather is neither compressed nor wrinkled at the edge of the inner sole, which is held in precise registry with the edge of the last, the fastenings of the upper and welt 65 thus are uniform with respect to the last instead of being more or less irregular as often heretofore; and the subsequent operations, following from this, make the lines and margins of the finished shoe automatically 70 correct, uniform and perfect. Although only one illustrative embodiment of the invention is here shown, many variations may be made. It is intended that the patent shall cover by suitable expression in 75 the appended claims whatever features of patentable novelty exist in the invention disclosed.

In the accompanying drawings,

Figure 1 is a toe plate of a last embodying 80 the invention; Fig. 2 a side elevation in medial section; Figs. 3, 4, 5, 6, and 7 show successive stages on an enlarged scale. Figs. 8 and 9 are a plan and modification; and Fig. 10 an elevation of another modification. 85

Referring to the drawings, 10 indicates a portion of a wooden last having in its toe portion a plate 11 which may serve the functions of the customary toe plate and may be shaped or secured thereto in any ordinary 90 or suitable manner, as by screws 12, and which may have a hole 13 through which the inner sole may be tacked to the last as is customary, although the last may be provided with any other means that may be desired for holding the inner sole thereon. As represented in the drawing the inner sole is marked 14 and is held by tacks 15. The toe plate 11 is provided with spurs 16, of which five are shown, formed by being upset from the metal of the plate itself and being preferably triangular in shape, with a broad base integral with the toe plate and with points directed forward at an incline and sharpened sufficiently to enter the leather of 100 the inner sole. These spurs are set near the edge of the plate and do not necessarily rise above its surface enough to enter the inner sole more than a short distance, although if preferred they may be made to go nearly 105 110

or quite through it; nor do they need to enter the inner sole in the direction in which they are inclined. In fact it is preferable that they be capable of entering in a direction normal to the surface of the last as this permits the inner sole to be secured and tacked in its proper place on the last by ordinary methods, after which with a hammer the inner sole may be driven down on these 5 spurs so that they are sufficiently embedded in it and so that the inner sole lies flat on the toe plate. But while the inner sole is thus applied and might, before the shoe is made, be removed in the direction perpendicular 10 to the surface, the spurs are so shaped and set that the normal and customary direction of removal is by withdrawing the last from the inner sole in the inclined direction in which the spurs project. When in use they 15 20 constitute abutments against which those parts of the inner sole which are in front of them or beside them are pressed and whereon they find a firm stabilizing support during the operations of the lasting 25 machinery including the pulling over and the wiping. After these operations they serve a similar purpose during the welting operation; and when the toe tack of the inner sole is pulled from the last the stabilizer, 30 remaining embedded in the sole, holds it in its perfect position on the last and makes more perfect the work done in later operations, including the rough rounding where-in the rounder is by means of the stabilizer 35 40 assured of getting a uniform edge. Because of the perfect condition in which the parts are assembled and fastened thus far, the Goodyear stitcher machine is able to do a more perfect job and with the sole coming up to meet the welt rather than forcing the 45 welt down to meet the sole. In all of this no additional labor is required; the operations of the tacking, the pulling over and the wiping serve to embed the spurs more 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

and 2, but the sole engaging means may be of some other variety, as, for example, a surface having a multiplicity of small teeth 16' (Figs. 8, 9,) or even sandpaper 16'' (Fig. 10); but in every case the arrangement 70 should be such that engaging means is removable from the sole toward the rear, when the last is pulled from the shoe.

In the form preferred the blank of plate 11 is made in a punching press which cuts 75 the same to form, cuts a large hole 13 for the tack that is to fasten the sole, cuts small holes 17 through the plate at the point of each spur, and cuts two sides forming the blank triangle 16^a with blunt tip which is 80 to constitute each spur, displacing each said triangle from the body of the sheet of metal by bending up the point thereof. Said points may then be sharpened, if desired, as by grinding on a wheel, or filing, making 85 the form 16^b and the toe plate is then ready to be used in a last. The last maker in fitting the plate to the toe of the last pounds the spurs back into smoothness with general curvature of the plate as at 16^c so that the 90 whole is smooth and the last can conveniently be finished and polished. Thereafter by a suitable tool inserted through each hole 17, the point 16^c therein can be pried and bent upward to the desired incline which 95 may vary considerably according to preference, 45° being illustrated, and can be fastened there, to prevent its returning, by the driving of a tack 18 under it into the wood in a direction parallel to its under surface. 100 The incline is preferably thus fixed in about the same direction as the direction in which the toe of the last moves when it is pulled from the shoe.

Prying up of the point of the spur is facilitated if there be a shallow hole drilled in the wood of the last under it as at 19. It may be expected that the spurs will grow dull with use and with handling to which lasts are ordinarily subjected. This may be corrected easily by re-sharpening the spurs by filing or grinding. And when these are worn out other spurs which have been left in the plate in blank form from the beginning, in the form of 16^a or 16^c, can be bent 115 up and set for use.

The distinction is to be noted that the means employed for fastening the sole on the last, such as tacks, do not serve the purpose of the stabilizer, because such means 120 are not and cannot practically be located close to the edge where the points of the stabilizer are located and serve their function of holding stiff a thin inner sole that otherwise would slip and wrinkle. Tacks, for 125 example, if put where the points 16 are, would be under the parts of the upper which are turned over, and could not be extracted.

We claim as our invention:

1. A making last, the toe portion of which 130

is adapted for the sole to be secured to it, and in addition has, near the edges of its bottom surface, a plurality of projections from said surface arranged to pierce the 5 tread face of the insole, thereby preventing longitudinal and transverse shifting of the edges thereof relative to the edges of said bottom surface, and arranged to point uniformly in a direction whereby they are 10 adapted to be withdrawn from the insole uniformly by initial withdrawal movement of the last as a unit from the shoe.

2. A making last having at its toe portion a plurality of unyielding projections extending from its bottom surface near the edges thereof, constructed and arranged to pierce the tread face of the insole and thus to prevent longitudinal and transverse shift of the edges of the toe thereof relative to 20 the last, said projections being arranged pointing uniformly and pointing approximately in the direction opposite to that of the initial withdrawal movement of the last as a unit from the shoe.

3. The combination, with a making last adapted to fill the toe of a shoe, removable therefrom as a unit, and arranged to receive means for securing the sole to the last, of a plurality of rigid spurs projecting from 30 the bottom surface of the last and adapted to pierce edge portions of the tread face of the sole and thus to prevent the movement of said edge portions inward from the edge of the last.

4. The combination, with a making last adapted to fill the toe of a shoe, removable therefrom as a unit, and arranged to receive means for securing the sole to the last, of a plurality of rigid spurs projecting from 40 the bottom surface of the last and adapted to pierce edge portions of the tread face of the sole and thus to prevent the movement of said edge portions inward from the edge of the last, said spurs all having backs 45 sloping to the rear portion of the surface of the last from which they project.

5. The combination, with a making last adapted to fill the toe of a shoe, removable therefrom as a unit, and arranged to receive means for securing the sole to the last, of a rigid spur projecting from the bottom surface of the last and adapted to pierce the edge portion of the tread face of the insole forward of the said securing means 50 and close to the edge at the point of the toe, in the position which the edge of the upper overlies when lasted, thereby preventing movement of the edge of the insole inward from the edge of the last; said spur being

adapted for becoming disengaged from the 60 insole by the withdrawal movement of the last as a unit from the shoe.

6. A plate arranged to be secured fast on the bottom of the toe portion of the last and having one or more spurs struck up 65 therefrom near the edge, adapted to engage the sole and obstruct movement of the edge portion thereof inward from the edge of the last.

7. A plate arranged to be secured fast on 70 the bottom of the toe portion of the last and having one or more spurs struck up therefrom near the edge, said spurs being adapted to engage the sole and obstruct movement of the edge portion thereof inward 75 from the edge of the last; and said plate having holes through it at the points of the spurs.

8. A plate arranged to be secured fast on the bottom of the toe portion of the last 80 and having one or more spurs struck up therefrom near the edge, said spurs being adapted to engage the sole and obstruct movement of the edge portion thereof inward from the edge of the last, and a prop 85 driven into the last under and supporting each spur.

9. A method of making an insole retaining last comprising the making of a plate to fit the toe of the last with points set out 90 from the surface of the plate; securing the same on the last; forming it as a part of the last including driving the points back into the surface thereof; finishing the last; and thereafter lifting said points. 95

10. A method of making an insole retaining last comprising the making of a plate to fit the toe of the last with points set out from the surface of the plate; securing the same on the last; forming it as a part of the 100 last including driving the points back into the surface thereof; finishing the last; and thereafter lifting said points, and inserting props under the lifted points.

11. A last having a spur or spurs rigidly 105 arranged at the edge of the bottom of its toe portion with forward and side faces of the spur or spurs sufficiently steep to pierce and to resist longitudinal and transverse shift of the sole, and with its or their rear 110 faces having a sufficiently gentle slope to facilitate its or their withdrawal as a unit with the last over the surfaces of the sole.

Signed at Boston, Massachusetts, this twenty-third day of January, 1920. 115
